[57] **CLAIM**

The ornamental design for a motor, as shown and described.

DESCRIPTION

FIG. 1 is a top perspective view of a motor showing my new
design;

FIG. 2 is a top plan view thereof; and,

FIG. 3 is an elevational view thereof, the opposite and
adjacent elevations being identical in appearance.

The undisclosed bottom forms no part of the claimed design.

In the specification, views which are now shown in the
drawings do not form part of the applicant's invention.
